DESIGN FOR A DRESS

Harry Zinn, New York, N. Y.

Application November 28, 1938, Serial No. 81,416

Term of patent 3½ years

To all whom it may concern:

Be it known that I, Harry Zinn, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the specific dress disclosed, of the specific draped folds on the front waist portion and on the sleeves as shown.

I claim:

The ornamental design for a dress, substantially as shown and described.

HARRY ZINN.
